Fig. 1

The design is characterized by having a generally spherical head on a vertical neck-like pedestal, the face of the clock lying in a plane intersecting the head at a small angle to the vertical pedestal.

We claim:

The ornamental design for a clock, substantially as shown and described.
